UNITED STATES PATENT OFFICE.

LOWELL F. LINDLEY, OF CHICAGO, ILLINOIS.

ROOFING.

Application filed June 10, 1926. Serial No. 114,958.

This invention relates to covering or roofing material which may be utilized for any uses for which it may be adapted but is particularly directed to the type commonly known as roll roofing. Roll roofing as heretofore made usually consists of long sheets or strips of suitable material, such as asphalt roofing. When these strips are laid on the roof, they are overlapped and nailed to form the joints, but there is always more or less tendency toward warping or raising between the nails with a consequent liability of leaking on account of rain or snow being driven past the joint through such raised portions. It has also been proposed to form interlocking edges but these have been found impractical, as it is difficult if not impossible to properly interlock and fasten long strips of such material.

In accordance with the present invention, I provide an improved roofing which will overcome the objections to such previous forms and which when laid will provide a more perfect covering.

The objects of this invention are to provide a new and improved roofing material which may be conveniently and cheaply manufactured and which will be particularly efficient and durable in use; to provide roll roofing having a fold or hem-like border or borders formed by folding over the edge or edges; to provide a strip of covering or roofing material having one edge folded, which edge is adapted to coact with the adjacent straight edge of a corresponding overlapping strip; to provide roll roofing which may be marked or colored to simulate shingles and which when laid will have the appearance of shingling; and to provide such other advantages and novel features as will be described more fully hereinafter.

In the accompanying drawings illustrating this invention;

Figure 1 is a plan view showing a strip of roll roofing embodying this invention;

Figure 2 is a side view showing the material as applied to a roof;

Figure 3 is an enlarged sectional detail taken on the line 3—3 of Figure 1;

Figure 4 is an enlarged sectional detail taken on the line 4—4 of Figure 2; and

Figure 5 is a plan view showing a modified form of construction, or showing one-half of the strip illustrated in Figure 1 after the strip has been cut in two.

In the form of the invention as shown in

Figure 1, the strip or piece 6 represents any suitable covering or roll roofing material, such as asphalt roofing or the like. The surface of this strip is preferably covered, as shown at 7, with ground stone, mineral grits or any of the usual materials adapted for this purpose. Such covering extends approximately across the strip but the uncovered edges or borders are left along either side, as indicated at 8 in Figure 3. These edges or uncovered portions are then folded over and pressed tightly against the face of the strip to form the folds 9 which extend along the entire length of the roofing. This folding and pressing of the edges may be done in any suitable manner. The surface 7 may be marked as indicated at 10 with any suitable marking or coloring in order to give the appearance of shingles or for the purpose of embellishing or improving the appearance of the roofing. When the strip or roll has been completed, it is then split along the center, as shown at 11 to form two duplicate or similar strips, each having one plain edge and one rolled or hemmed edge. While the rolled edge or flaps 9 will in most cases remain in position by being pressed down, they may also be cemented or otherwise fastened if desired.

When my improved roofing is applied, the lower strip, as shown in Figures 2 and 4, will be laid with the roll or flap along the upper edge and the straight edge of the next succeeding strip will be placed over this flap so that the roofing nails 12 will pass through the lower edge of the upper strip and through the flap and adjacent portion of the lower strip.

The roofing may be readily applied in this manner and when so applied, the flap or fold 9 will prevent or tend to prevent water, snow, or the like from being driven in through the joint formed between the strips. There may be a slight tendency toward buckling or raising of the lower edge of the upper strip when the nails are driven, but the flap will also tend to raise or in any event will tend to make a more perfect joint or closure between the strips. These flaps may be made of any desired width, but I have found that for ordinary purposes they may be made approximately two inches wide to effectively serve the purposes intended. When the strips are provided with transverse markings 10 to simulate shingles, such markings may be arranged in staggered re-

lation, as shown in Figure 2, and the double thickness shown along the joint further enhances the shingle effect, as it gives the appearance of the thickened butts of shingles.

5 Instead of making a double width roll, as shown in Figure 1, a single width may be made, as shown in Figure 5, with the flap or fold 9 along one edge only, and the other edge left straight or without such flap.

10 It is apparent that my improved roofing or covering may be made in various sizes and may be made of any suitable material and may be marked or decorated to simulate shingles or in any desired manner, and therefore I do not wish to be limited to the exact form or arrangement herein described, except as specified in the following claims, in which I claim:

1. A roof covering comprising separate 20 strips laid substantially parallel to the eaves, each strip having its upper edge only folded back upon itself to provide a joint or flap forming an abutment against the ingress of water thereover, with the lower por-

tion of the adjacent strip overlapping said flap and nails through such overlapping portions.

2. A roof covering comprising strips of felt laid substantially parallel to the eaves with a water-proofing coating on each strip 30 extending on the outside face to a line adjacent to the upper edge leaving an uncoated portion forming a flap, which flap is folded over onto the adjacent coated face, the lower edge of the next strip being placed over and 35 coinciding with the lower edge of the flap.

3. A roof covering comprising overlapping strips laid substantially parallel to the eaves, each strip having a water-proof coating extending from the lower edge to a line 40 at a distance from the upper edge forming an uncoated flap which is turned over against its coated face, and fastening means inserted through the overlapping strip portions and said flap thereby forming a seal 45 between the overlapping strips.
